UNITED STATES PATENT OFFICE

92,966

DESIGN FOR A SHOE

Dominick La Valle, New York, N. Y.

Application June 6, 1934, Serial No. 52,080

Term of patent 3½ years

To all whom it may concern:

Be it known that I, DOMINICK LA VALLE, a citizen of the United States and resident of New York city, in the county of New York, and State of New York, have invented a new, original, and ornamental Design for a Shoe, of which the following is a specification, reference being had to the accompanying drawing forming part thereof, in which, Figure 1 is a perspective front view, and Figure 2 a perspective side view, of a shoe showing my new design.

I claim:
The ornamental design for a shoe as shown.
Dated June 1, 1934.

DOMINICK LA VALLE.
